UNITED STATES PATENT OFFICE.

CHARLES RUPP, OF PHILADELPHIA, PENNSYLVANIA, ASSIGNOR TO J. S. THORN COMPANY, OF PHILADELPHIA, PENNSYLVANIA, A CORPORATION OF PENNSYLVANIA.

MULTIPLE-SASH-OPERATING MECHANISM.

1,380,309.

Specification of Letters Patent.

Patented May 31, 1921.

Application filed May 15, 1919. Serial No. 297,400.

To all whom it may concern:

Be it known that I, CHARLES RUPP, a citizen of the United States, residing at 726 Vernon road, Stenton, Germantown, in the city and county of Philadelphia and State of Pennsylvania, have made a certain new and useful Improvement in Multiple - Sash - Operating Mechanism, whereof the following is a specification, reference being had to the accompanying drawings.

My invention relates to mechanism which may be applied to uniformly adjustably open and close what is called a "continuous" window sash, or a series of distinct sashes or shutters, for controlling the effective area of any opening, by means of an endless belt.

My invention includes unit groups of mechanism, all supported at intervals in the length of the opening to be controlled, each comprising two right hand and two left hand levers, associated with links which couple said levers in pairs and respectively connect the right hand levers with the sash to the right of the support for said unit group, and connect the left hand levers with said sash to the left of said support, in mutually sustaining relation; so that each of said lever and link mechanisms supports its proportion of the weight of the endless belt aforesaid.

As hereinafter described, my invention includes means whereby the power for both opening and closing movement of the mechanism is transmitted by members which are under tension, such members including substantially rigid transmission rods which are coupled at their ends by flexible connectors, preferably chains, to form an endless belt; said rods being so arranged as to maintain the lines of tension with the minimum camber, and said connectors affording the necessary flexibility for the traverse of said belt around supporting pulleys at each end of the opening.

Although I have found it convenient to illustrate my invention in connection with window sashes which are hinged at their upper edges upon substantially horizontal axes; it is to be understood that I do not desire to limit myself to such embodiment, as the mechanism herein shown may be applied

to open and close sashes, shutters, or the like, hinged upon vertical axes.

My invention includes the various novel features of construction and arrangement hereinafter more definitely specified.

In said drawings: Figure I is a fragmentary plan view of a continuous window sash, with operating mechanism conveniently embodying my invention.

Fig. II is a fragmentary elevation of the inner side of the sash and mechanism shown in Fig. I.

Fig. III is a fragmentary, vertical sectional view, taken on the line III, III in Figs. I and II, showing the construction and arrangement of said sash and mechanism.

Fig. IV is a side elevation of one of the sash links which, in assembled position, directly connect the levers with the sash. Said links are all alike in shape and dimensions.

Fig. V is a side elevation of one of the outer right hand levers, which, in assembled position, is connected with the sash link shown in Fig. IV. The outer right and left hand levers are respectively differently shaped.

Fig. VI is a side elevation of one of the inner right hand levers. The inner right and left hand levers are respectively differently shaped.

Fig. VII is a side elevation of one of the lever coupling links; which, in assembled position, couple said levers shown in Figs. V and VI. Said coupling links are all alike in shape and dimensions.

Fig. VIII is a side elevation of one of the outer left hand levers.

Fig. IX is a side elevation of one of the inner left hand levers.

Fig. X is a fragmentary perspective view, showing the construction and arrangement of one of the pivotal clamp fittings, which respectively connect said endless belt with each of said paired lever and link mechanisms.

In said figures: 1 and 2 indicate respectively opposite end walls of a building having the side wall 3 connecting said end walls 1 and 2, and including the opening 4, the effective area of which is to be controlled. Said wall 3 has, at intervals of, say ten

feet, vertical columns 5, conveniently formed of pairs of angle irons opposed in rigid relation as shown in Figs. I and II. However, it is to be particularly noted, with reference to Fig. I, that said columns 5 are so spaced inwardly with respect to said opening 4 as not to interrupt the latter; so that said opening may be provided with a closure which is continuous past said columns. That construction and arrangement is advantageous in that such a single closure may be provided at less cost than a series of closures interrupted by columns. Said wall 3 also includes the horizontal top rails 7 and the horizontal bottom rails 8, conveniently secured in rigid relation with said vertical columns 5, by suitable angle clips 6, as indicated in Fig. III; also vertical end rails 9; framing said opening 4. Said rails 7 and 8 are connected with the end walls 1 and 2 by flashings 10 shown in Fig. I, and may include the stationary sash 11 and storm panels 12 at respectively opposite ends of the movable sash 14, which is fitted to close said opening 4. As indicated in Fig. III; said movable sash 14 includes the upper horizontal angle rail 15 provided with hinges 16, turning upon horizontal axes in connection with said top rail 7, which is stationary; and said sash 14, includes the bottom rail 18, connected with its upper rail 15 by vertical bars 19 and holds the series of glass panels 20.

Each of said vertical columns 5, of said wall 3, has a single fulcrum cross bar 22 which is rigidly mounted above the bottom rail 8 of said opening 4, as shown in Fig. III. As best shown in Fig. I; said bar 22 supports the fulcrums of the group of four levers 24, 25, 26 and 27. Said lever 24 is the outer right hand lever, shown in Fig. V, which has its free end directly pivotally connected with the inner end of the sash link 29, shown in Fig. IV. Said link 29 has its outer end directly pivotally connected with the bottom rail 18 of said sash 14. Said outer right hand lever 24 is pivotally connected, by the lever coupling link 31, with the inner right hand lever 25, by the pivotal clamp fitting 32, which, as shown in Figs. III and X, includes a pair of complementary, interlocked, clamp plates which are compressed by the pivot bolt 34, so as to rigidly connect said fitting with the transmission rod 35, which forms the major part of the lower reach of the endless belt aforesaid; which, under tension in the direction of the arrow in Fig. II, carries said fitting 32 to the left, to the position shown in Figs. I and II, thus operating said right hand pair of levers and said links, to pull said sash 14 shut; to the position shown in the drawings. Tension upon said rod 35, in the opposite direction, shifts said lever and link mechanism to open said sash 14.

Said lever 26 is the outer left hand lever, shown in Fig. VIII, which has its free end directly pivotally connected with the inner end of one of the sash links 29, shown in Fig. IV. Said link 29 has its outer end directly connected with the bottom rail of said sash 14. Said outer left hand lever 26 is pivotally connected, by the lever coupling link 31, with the inner left hand lever 27, by another pivotal clamp fitting 32; so as to rigidly connect that fitting with the transmission rod 37, which forms the major part of the upper reach of the endless belt aforesaid, of which said rod 35 forms the lower reach. Said rod 37, under tension in the direction of the arrow in Fig. II, carries its fitting 32 to the right, to the position shown in Figs. I and II, thus operating said left hand pair of levers and said links, to pull said sash 14 shut; to the position shown in the drawings. Tension upon said rod 37, in the opposite direction, shifts said lever and link mechanisms to open said sash 14. It is to be particularly noted that the construction and arrangement of said lever and link mechanisms above described is such that the levers 25 and 27 and links 31 overlap in a mutually sustaining relation, in support of said transmission rods 35 and 37.

That is to say, tension upon said endless belt, including said rods 35 and 37, such as to increase the horizontal distance between the respective pivotal fittings 32 on said rods, draws the shutter 14 into closed position, whereas, tension upon said rods in the opposite direction, tending to decrease the horizontal distance between their respective pivotal fittings 32, operates said lever and link mechanisms to open said sash 14.

Said transmission rods 35 and 37 may be coupled by any convenient means to effect the movements thereof above described; however, I prefer to operate them by an endless belt having the specific construction and arrangement which I have illustrated.

As best shown in Fig. II; said transmission rod 35 has, at its left hand end, the turnbuckle 39 and hook bolt 40 for adjustable connection with the flexible connector 41; conveniently an ordinary oval link chain, the accidental disengagement of which is prevented by the keeper clamp 42 extending across the bight of said hook bolt 40. Said chain 41 extends freely around the sheave 45 which is journaled in the frame 46, pivotally connected by the bolt 47 and the brackets 48 with said building wall 1.

The opposite end of said transmission rod 35 is provided with the hook 50 in connection with the flexible connector 51 conveniently a sprocket chain, the accidental disengagement of which is prevented by the keeper clamp 52 extending across the bight of said hook 50. Said chain 51 extends

around and is engaged by the sprocket wheel 54 which is journaled in the frame 55 pivotally connected by the bolts 56 and brackets 57 with said building wall 2. Said sprocket 5 wheel 54 is rigidly connected with the worm gear 59 and thus arranged to be turned by the worm 60 which is journaled in said frame 55 and provided with the sprocket wheel 61 having the endless chain 63 engaged thereon and pending in convenient position to be pulled by the operator.

The opposite ends of said belt chains 41 and 51 are connected by said transmission rod 37 and its appurtenances which, as 15 shown in Fig. II, are precisely like the transmission rod 35 and its appurtenances, except that they are in reversed position.

The extent of movement of said endless belt, comprising the transmission rods 35 and 20 37, and chains 41 and 51, is limited by the two stops 65 and 66 upon said chain 51; each of said stops including a pair of angle plates connected by a bolt extending through a link of that chain, as shown in 25 Fig. II.

Said mechanism is operated as follows:

It being desired to open said sash 14; the portion of said chain 63 remote from the observer of Fig. II is drawn downwardly by 30 the operator, thus turning said worm gear 59 in the direction of the arrow on that figure, and thereby drawing the lower reach of said chain 51 and the transmission rod 35 to the right, and simultaneously, by means 35 of the chain 41, drawing said transmission rod 37 to the left, in Fig. II. The effect of such movement is to decrease the horizontal distance between the respective pivotal fittings 32 on said rods 35 and 37, and thus 40 swing the levers 24, 25, 26 and 27 outwardly and, by means of the links 29, thrusting said sash uniformly upon opposite sides of the vertical column 5, cause said sash to swing outwardly upon its hinges 16. Although 45 the extreme extent of such movement is limited by the stop 65, upon the lower reach of said chain 51, encountering the frame 55; such movement may be stopped with the sash in any desired intermediate position; engagement of said worm wheel 59 with said 50 worm 60 preventing accidental displacement of said sash from any position in which it may be set by the operator. Reverse movement of said sash operating mechanism, to close said sash 14, is effected by the operator pulling downwardly upon the reach of the chain 63 nearest to the observer of Fig. II, and the extreme extent of such movement is limited by said stop 66, engaged with the upper reach of said chain 51, encountering said frame 55. Although 55 said sash 14 is illustrated in closed position, with said stop 66 slightly removed from said frame 55; it is to be understood that said stop 60 is placed in that position upon said chain to

compensate for lost motion incident to wear of the several transmission elements, but said stop 66 is so positioned as to prevent any such strain upon the transmission elements as would suffice to break them or said 70 sash. Of course, the turnbuckles 39 may be readily adjusted, at any time, to take up any increment in slack of the endless belt, so as to continuously maintain the same at the proper tension. Moreover, although said 75 stops 65 and 66 are only adjustable upon the chain 51, in steps equal to the length of a link of that chain; more precise adjustment of the position of said stops with respect to said frame 55, may be effected by 80 manipulation of said turnbuckles 39. Moreover, by manipulation of said turnbuckles 39, the relative position of said rods 35 and 37 may be adjustably varied to precisely adjust the relation of the lever mechanism to 85 said closure.

Although I prefer to make the levers and links above described of ordinary commercial shapes of iron or steel bars which may be cut and riveted together in the relation 90 shown in Figs. IV, V, VI, VIII and IX, and to form said pivotal clamps 32 of castings; I do not desire to limit myself to the specific details of construction and arrangement herein set forth, as it is obvious that 95 various modifications may be made therein, without departing from the essential features of my invention, as defined in the appended claims.

Although I have found it convenient to 100 illustrate my invention with reference to a continuous window sash, as above explained, it is applicable to move any structure which may be used to control the effective area of any opening and, therefore, in the following 105 claims, I use the term "closure" as descriptive of any such movable structure.

I claim:

1. The combination with a structure having an opening, the effective area of which is 110 to be controlled; of a closure arranged in movable relation with said opening; a column intermediate of the extent of said opening; a fulcrum cross bar on said column; a group of four levers, comprising oppositely 115 counterbalanced pairs, each having a bifurcated end fulcrumed upon said cross bar; lever coupling links pivotally operatively connecting said levers in pairs, upon respectively opposite sides of said column; said 120 lever coupling links and inner levers being overlapped in mutually sustaining relation; links respectively pivotally connected at one end with the free ends of the outer levers of said pairs, and pivotally connected at the 125 other end with said closure; clamp fittings at the pivotal connections of said coupling links with the inner levers of said pairs, adapted for adjustable engagement with transmission rods; transmission rods re- 130

spectively engaged by said clamp fittings, and forming opposite reaches of an endless belt, including flexible connectors between said transmission rods, at the end bights of said belt; each of said rods having a hook in unitary relation therewith at one end engaged with one of said connectors, and a hook connected with said rod by a turnbuckle at the other end, and in engagement with the other of said connectors; one of said connectors being a sprocket chain; wheels supporting said belt by engagement with said flexible connectors; one of said wheels being a sprocket wheel engaging said sprocket chain; a worm wheel carried by said sprocket wheel; a worm engaging said worm wheel; and means whereby said worm may be rotated, to shift said belt; frames supporting said wheels at the opposite ends of said belt; and means pivotally connecting said frames with said structure; two adjustable stops upon said sprocket chain, arranged to limit the movement of said belt, with reference to the frame in which said sprocket wheel is journaled.

2. The combination with a structure having an opening, the effective area of which is to be controlled; of a closure arranged in movable relation with said opening; a column intermediate of the extent of said opening; a fulcrum cross bar on said column; a coupling links pivotally operatively connecting said levers in pairs, upon respectively opposite sides of said column; said coupling links and the inner levers of said pairs being overlapped in mutually supporting relation; links respectively pivotally connected at one end with the free ends of the outer levers of said pairs, and pivotally connected at the other end with said closure; clamp fittings at the pivotal connections of said coupling links with the inner levers of said pairs, adapted for adjustable engagement with transmission rods; and transmission rods respectively engaged by said clamp fittings, and forming opposite reaches of an endless belt, including flexible connectors between said transmission rods, at the end bights of said belt.

3. The combination with a structure having an opening, the effective area of which is to be controlled; of a closure arranged in movable relation with said opening; a column intermediate of the extent of said opening; a fulcrum cross bar on said column; a pair of levers, each having a bifurcated end fulcrumed upon said cross bar; a lever coupling link pivotally operatively connecting said levers; a link pivotally connected at one end with the free end of one lever of said pair, and pivotally connected at the other end with said closure; a compress-

sible bifurcated clamp fitting forming the pivotal connection of said coupling link with the other lever of said pair, and adapted for adjustable engagement with a transmission rod; and a transmission rod engaged by said clamp fitting, and arranged to actuate said levers to move said closure.

4. The combination with a structure having an opening, the effective area of which is to be controlled; of a closure arranged in movable relation with said opening; a lever pivotally connected with said closure by a link; a second lever pivotally connected with said first lever, by another link; said second lever being L-shaped and having a portion normally extending parallel with and supporting said second link, and a portion extending transversely thereto; and means arranged to actuate said levers to move said closure.

5. The combination with the closure for an opening; of means arranged to move said closure and hold it in adjusted position, including two transmission rods forming opposite reaches of an endless belt; flexible

connectors between said transmission rods, at the end bights of said belt; each of said rods having a hook in unitary relation therewith at one end engaged with one of said connectors, and a hook connected with said sprocket chain; wheels supporting said belt by engagement with said flexible connectors; one of said wheels being a sprocket wheel engaging said sprocket chain; a worm gear carried with said sprocket wheel; a worm engaging said worm gear; means whereby said worm may be rotated, to shift said belt; frames supporting said wheels at the opposite ends of said belt; means pivotally supporting said frames; and two adjustable stops upon said sprocket chain, arranged to limit the movement of said belt, with reference to the frame in which said sprocket wheel is journaled.

6. The combination with the closure for an opening; of means arranged to move said closure and hold it in adjusted position, including two transmission rods forming opposite reaches of an endless belt; flexible connectors between said transmission rods, at the end bights of said belt; each of said rods having a hook in unitary relation therewith at one end engaged with one of said connectors, and a hook connected with said rod by a turnbuckle at the other end, and in engagement with the other of said connectors; one of said connectors being a sprocket chain; wheels supporting said belt by engagement with said flexible connectors; one of said wheels being a sprocket wheel engaging said sprocket chain; a worm gear carried by said sprocket wheel; a worm en-

gaging said worm gear; means whereby said worm may be rotated, to shift said belt; frames supporting said wheels at the opposite ends of said belt; and means pivotally supporting said frames.

7. An article of manufacture, adapted to operate the closure for an opening, comprising an endless belt, including transmission rods, forming opposite reaches thereof; flexible connectors between said rods, in the bights of said belt; each of said rods having a hook in unitary relation therewith at one end engaged with one of said connectors, and a hook connected with said rod by a 10 turnbuckle at the other end, and in engagement with the other of said connectors; one of said connectors being a sprocket chain.

8. An article of manufacture, adapted to operate the closure for an opening, comprising an endless belt, including transmission rods, forming opposite reaches thereof; flexible connectors between said rods, including sprocket chains in the bights of said belt; sprocket wheels engaging said chains; and stops adjustably engaged with one of 20 said chains arranged to limit the movement of said belt by said wheels.

In testimony whereof, I have hereunto signed my name at Philadelphia, Pennsylvania, this 25th day of March, 1919.

CHARLES RUPP.
